CATHODE-RAY APPARATUS

Merton R. Miller, Evanston, Ill., assignor to
 Western Electric Company, Incorporated, New
 York, N. Y., a corporation of New York

Application January 9, 1943, Serial No. 471,906

8 Claims. (Cl. 315—30)

This invention relates to a cathode ray apparatus, and more particularly to an apparatus for maintaining a constant beam intensity of cathode rays with varying sizes of patterns.

In many types of oscillographs a change in the dimensions of the cathode ray pattern results in a decrease or increase in the degree of illumination, depending upon whether the dimensions are increased or decreased and therefore an adjustment must be made in the beam intensity to obtain uniform illumination.

An object of the present invention is to provide effective means for varying the cathode ray intensity as the dimensions of the pattern are varied.

In accordance with one embodiment of the invention a portion of the energy provided for deflecting the cathode ray beam is rectified and utilized to increase the cathode ray intensity when the degree of deflection is increased and to decrease the intensity when the degree of deflection is decreased.

Other objects and advantages will appear from the following description taken in conjunction with the accompanying drawing in which the single figure is a circuit diagram of an oscillograph embodying means for automatically varying the cathode ray intensity as the pattern size is varied.

Referring to the drawing a cathode ray oscillograph is shown including a cathode ray tube 5 provided with a fluorescent screen having a band electrode 6 which may be energized positively relative to a cathode 7 by means of a full wave rectifier 8 connected to a transformer 9. This rectifier may also provide anode current for tubes 11, 12, 13 and 14 which are preferably of the tetrode type.

A pair of deflector plates 15 of the cathode ray tube are connected to the anode circuits of tubes 11 and 12 to impart a vertical deflection along the Y-axis to the cathode ray beam, the grid circuit of tube 11 being connected to a source of energy to be analyzed. Similarly, deflector plates 16 are connected to the anode circuits of tubes 13 and 14 to impart a horizontal deflection along the X-axis of the cathode ray beam, the grid circuit of tube 13 being connected to a source of sweep current.

The cathode ray tube is also provided with a pair of accelerating electrodes 17 and 18 and a focusing electrode 19. Energy is supplied to the focusing electrode 19 as well as to a grid or modulating electrode 21 through a rectifier 22 also connected to transformer 9. The anode circuit

of rectifier 22 is connected to the modulating grid 21 through a pair of resistances 23 and 24 and the cathode is supplied with energy from this circuit through potentiometer resistances 5 25 and fixed resistances 27, 28 and 29. The circuit thus far described is conventional and therefore greater detail of description is not deemed necessary. In such a circuit the intensity of the beam is adjusted manually by adjusting the potential on the modulating grid through manipulation of the potentiometer resistance 25 or by varying the resistance through a switch arm 31. Hence, if the beam current is adjusted to a value giving a satisfactory pattern intensity for 10 a small pattern, the pattern intensity will be diminished if the pattern is expanded and be too dim. Similarly, if the intensity is set satisfactorily for a large pattern, the intensity may increase to a value which will burn or seriously decrease the life of the fluorescent phosphor screen when the pattern is contracted. It is, therefore, evident that an increased cathode ray tube life, as well as increased facility of operation may be had if the beam current is controlled automatically 15 so as to maintain constant pattern intensity independent of pattern expansion.

This is accomplished in accordance with the present invention by supplying a potential to the modulating grid which varies in accordance with 20 the potential on the deflector plates. For this purpose a rectifier 36 is provided having two anodes 37 and 38, one of which is connected through a condenser 39 and resistance 41 to one of the deflector plates 16, and the other is connected 25 through condenser 42 and resistance 43 to one of the deflector plates 15. The anodes 37 and 38 are bridged by a center tapped resistance 44 serving as the negative output point of the rectifier. The cathodes 45 of the rectifier are connected in parallel and the output of the rectifier 30 is connected to a resistance 46 shunted by a condenser 47 in the modulating grid circuit of the cathode ray tube. Thus portions of the voltages on the horizontal and vertical deflector plates 40 are rectified, smoothed by condenser 47 and applied to the modulating grid 21 to make it more positive for higher deflector plate voltages and less positive for lower deflector plate voltages. The degree of compensation may be controlled 45 by the values of the resistances 41 and 43 in the leads to the horizontal and vertical leads. The circuit just described gives an average compensation for all frequencies to keep the light intensity of the pattern on the screen uniform as the size 50 of the pattern is varied.

While but one embodiment of the invention has been described and illustrated, it will be evident that many changes and modifications may be made therein without departing from the spirit and scope of the invention.

What is claimed is:

1. A cathode ray apparatus comprising a cathode ray tube having deflector electrodes and a modulating electrode, means for applying a uni-directional voltage to said modulating electrode, a rectifier and a resistance connected to said modulating electrode to receive the uni-directional output of said rectifier therethrough, said rectifier being connected to rectify a portion of energy applied to said deflecting electrode whereby the luminosity of the cathode ray will vary in accordance with the size of the pattern.

2. A cathode ray apparatus comprising a cathode ray tube having deflector electrodes and a modulating electrode, means for applying a deflecting voltage to said deflector electrode, means for applying a uni-directional voltage to said modulating electrode, a rectifier, means for applying an average portion of said deflector voltage to said rectifier, and means for applying rectified uni-directional voltage to said modulating electrode.

3. A cathode ray apparatus comprising a cathode ray tube having deflector electrodes and a modulating electrode, means for applying a deflecting voltage to said deflector electrode, means for applying a voltage to said modulating electrode, a rectifier, means for applying a portion of said deflector voltage to said rectifier, and means for applying a unidirectional average value of said rectified voltage to said modulating electrode.

4. A cathode ray apparatus comprising a cathode ray tube having deflector electrodes and a modulating electrode, means for applying a deflecting voltage to said deflector electrode, means for applying a voltage to said modulating electrode, a rectifier, means for applying a portion of said deflector voltage to said rectifier, and means for applying a voltage proportional to the average value of said deflecting voltage from said rectifier to said modulating electrode.

5. A cathode ray apparatus comprising a cath-

ode ray tube having deflector electrodes and a modulating electrode, a rectifier having a pair of anodes, a condenser connecting each of said rectifier anodes to one of said deflector electrodes, a resistance connected to said modulating electrode to receive the uni-directional output of said rectifier and apply a voltage to said modulating electrode proportional to the average value of the voltage applied to said deflecting electrodes

5 10 whereby the luminosity of the cathode ray will vary in accordance with the size of the pattern.

6. A cathode ray apparatus comprising a cathode ray tube having deflecting electrodes and a modulating electrode, a rectifier, means for applying a voltage to said rectifier proportional to a voltage applied to said deflector electrodes, and means for applying an average uni-directional rectified voltage to said modulating electrode.

7. A cathode ray apparatus comprising a cathode ray tube having horizontal and vertical deflector electrodes and a modulating electrode, a full wave rectifier having two sets of rectifying electrodes, a condenser connecting one of said horizontal deflector electrodes to a rectifier electrode, a condenser connecting one of said vertical deflector plates to a rectifier electrode, a center tapped resistance bridging said rectifier electrodes to provide a rectified voltage outlet, and means for applying said rectified voltage to said modulating electrode.

8. A cathode ray apparatus comprising a cathode ray tube having horizontal and vertical deflector electrodes and a modulating electrode, a full wave rectifier having two sets of rectifying electrodes, a condenser connecting one of said horizontal deflector electrodes with one of said rectifier electrodes, a condenser connecting one of said vertical deflector electrodes with another of said rectifier electrodes, a center tapped resistance bridging said rectifier electrodes to provide a rectified voltage outlet, a resistance and condenser in parallel connected to said modulating grid, and means for applying a rectified voltage from said rectified voltage outlet to said parallel resistance and condenser of the modulating electrode.
